UNITED STATES PATENT OFFICE.

JESSIE M. CARTER, OF BALTIMORE, MARYLAND.

DESIGN FOR A PORTABLE WRAP-HANGER.

50,339.

Specification for Design.

Patented Oct. 5, 1920.

Application filed October 30, 1919. Serial No. 334,540. Term of patent 14 years.

To all whom it may concern:

Be it known that I, JESSIE M. CARTER, a citizen of the United States, and a resident of the city of Baltimore, county of Baltimore, and State of Maryland, have invented a new, original, and ornamental Design for a Portable Wrap-Hanger, of which the following is a specification, reference being had to the accompanying drawing, forming part thereof.

The figure is a front elevation of a portable wrap hanger showing my new design.

I claim:

The ornamental design for a portable wrap hanger, as shown.

JESSIE M. CARTER.
